US00D645557S

(12) **United States Design Patent**
Scheiner et al.

(10) **Patent No.:** US D645,557 S
(45) **Date of Patent:** ** Sep. 20, 2011

(54) **PAIRED SET OF PRONGS FOR PATIENT INTERFACE**

(75) Inventors: **Rupert Christian Scheiner**, Davidson (AU); **Christopher Scott Skipper**, West Ryde (AU); **Gregory Scott Smart**, Randwick (AU); **Steven John Lubke**, Stanmore (AU)

(73) Assignee: **ResMed Limited**, Bella Vista (AU)

(**) Term: **14 Years**

(21) Appl. No.: **29/277,367**

(22) Filed: **Feb. 22, 2007**

(57) **CLAIM**

The ornamental design for a paired set of prongs for a patient interface, as shown and described.

DESCRIPTION

FIG. 1 is a front perspective view of a paired set of prongs for a patient interface according to a first embodiment of our design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front perspective view of a paired set of prongs for a patient interface according to a second embodiment of our design;

FIG. 10 is a bottom perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof;

FIG. 16 is a right side view thereof;

FIG. 17 is a front perspective view of a paired set of prongs for a patient interface according to a third embodiment of our design;

FIG. 18 is a bottom perspective view thereof;

FIG. 19 is a front view thereof;

FIG. 20 is a rear view thereof;

FIG. 21 is a top view thereof;

FIG. 22 is a bottom view thereof;

FIG. 23 is a left side view thereof; and,

FIG. 24 is a right side view thereof.

FIGS. 1-24 use stippling which is not part of the claimed design.
